US00D801929S

(12) **United States Design Patent** (10) Patent No.: **US D801,929 S**
(45) Date of Patent: ** Nov. 7, 2017

(54) **VIDEO CAMERA CABLE ADAPTER AND CONNECTOR**

(71) Applicants: **Kevin E. Halleck**, Santa Barbara, CA (US); **Greg M. Chambers**, San Luis Obispo, CA (US)

(72) Inventors: **Kevin E. Halleck**, Santa Barbara, CA (US); **Greg M. Chambers**, San Luis Obispo, CA (US)

(73) Assignee: **Karl Storz Imaging, Inc.**, Goleta, CA (US)

(**) Term: **15 Years**

(21) Appl. No.: **29/530,990**

(22) Filed: **Jun. 22, 2015**

(51) LOC (10) Cl. **13-03**

(52) U.S. Cl. **D13/133**

(57) **CLAIM**

The ornamental design for a video camera cable adapter and connector, as shown and described.

DESCRIPTION

FIG. 1 is a top, front and right side isometric view of a video camera cable adapter and connector in accordance with the new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken line portion of the figure drawings is included to show portions of the article and forms no part of the claimed design.

1 Claim, 7 Drawing Sheets
